UNITED STATES PATENT OFFICE.

PAUL H. JONES, OF WHITE PLAINS, NEW YORK.

TOY.

1,199,081.

Specification of Letters Patent. Patented Sept. 26, 1916.

Application filed May 4, 1914. Serial No. 836,217.

To all whom it may concern:

Be it known that I, PAUL H. JONES, a citizen of the United States of America, and resident of White Plains, in the county of Westchester and State of New York, have invented certain new and useful Improvements in Toys, of which the following is a specification.

This invention relates to toys and particularly to figure toys of the animated type.

An object of this invention is to provide novel means whereby the representation of an animal may have parts thereof, such as its legs articulated so that they may be capable of movement with relation to the body portion of the toy or animal, novel means being provided whereby movement of one of the members can be communicated to another member, and vice versa. While, hereinafter, the specification will refer to the articulated member as the leg of the animal, it is to be understood that the term is used generically and means any support for the body, whether the same simulate the legs of a man or animal or whether it simulate the arms and legs of a man in a stooping posture, with the hands resting on the ground and acting as a support for the body.

With the foregoing and other objects in view, the invention consists in the details of construction and in the arrangement and combination of parts to be hereinafter more fully set forth and claimed.

In describing the invention in detail, reference will be had to the accompanying drawings forming part of this specification, wherein like characters denote corresponding parts in the several views, and in which—

Figure 1 illustrates a view in elevation of a toy embodying the invention; Fig. 2 illustrates an underneath plan view of that part of the toy simulating a horse; Fig. 3 illustrates a perspective view of the upper end of one of the legs; Fig. 4 illustrates a vertical central sectional view of part of the device shown in Fig. 3; Fig. 5 illustrates a perspective view of two cranks with the connection shown in dotted lines, whereby the motion of one crank is communicated to the other; Fig. 6 illustrates a view in elevation, embodying a modified construction; and Fig. 7 illustrates a plan view of the invention shown in Fig. 6. Fig. 8 illustrates a

perspective view of the cranks showing fragments of the bearings by which they are connected to a frame.

In these drawings 10 denotes the representation of a toy cart having shafts 11 between which a figure 12 simulating the body of a horse is stationed and secured to the shafts by a tie-rod 13 which passes through the body 12 and has its ends looped around the shafts 11 for retaining the body in place.

In the present showing of the invention, the body 12 has studs 14 provided with heads 15, one of such studs being supplied for each leg 16. Each leg is provided with a guide 17 in which the head of the stud is slidable, the said guide comprising a metallic housing having lugs 18 and 19 at its ends, the former of which is secured to the top of the leg by a fastening, such as 20, and the latter of which extends through an aperture 21 in the leg and has its end 22 bent at an angle to the main portion for the purpose of retaining it in position.

By reason of the use of the guide and lug for connecting a leg to a body, the said leg is permitted to oscillate and reciprocate so that the leg may move across the surface of the floor or ground by being elevated from contact therewith while advancing or stepping forward.

In order to insure proper frictional contact between the ends of the legs and the surface over which it is traveling, shoes 23 are applied to the lower ends of the legs, the said shoes being in the nature of rubber pads or other yielding material which will serve to increase the friction between the legs and the surface they engage.

For the purpose of causing the movement of one leg to be communicated to the other, the rear legs are connected by a crank 24 and the front legs are connected by a crank 25, the said cranks having ends 26 and 27 respectively, which are rotatably mounted in the legs. The cranks 24 and 25 are double cranks in the form shown in Fig. 5 and they are connected by links 28 and 29, so that motion of one leg is communicated to the other. The angles of the crank-portions of each crank are at right angles to each other or approximately so, and the arrangement is such that when one of the legs is in contact with the surface over which it is traveling, it serves to communicate motion to the other three legs of the animal, although at certain

intervals two legs of the animal will be found to contact with the surface over which they are traveling but this engagement is but momentary and it is preferable therefore, 5 that the crank-portions of the cranks be in the relation indicated.

In the form shown in Figs. 6, 7, and 8 where there are a plurality of bodies 30, the said bodies are mounted on a frame 21 and 10 the frame is provided with a hinge 32 by which it is connected to the toy truck 33. The frame 31 at each side has the brackets 34 attached to its under side, and said brackets act as bearings for the crank shafts 15 35 and 36 which are journaled therein.

The legs 37 are connected to the bodies 30 in the manner described in connection with the disclosure of the form of the invention shown in Figs. 1, 2, 3 and 4 and the cranks 20 35 and 36 are applied to the rear and front legs respectively of the animal. In this form, there are no links connecting the front and rear cranks for, owing to the fact that there are a plurality of legs, one of which is 25 always in contact with the surface over which the toy is traveling, the engagement of one or the other of the rear legs with the surface at all times is assured and the movement of that leg can be communicated to the 30 other rear legs for raising and advancing the other of said legs. The same is true with respect to the front legs so that there is no necessity in this form for the use of the links.

35 The bodies may be attached to the frame in any appropriate way, as by screws 38, or the bodies may be secured to the frame by adhesive.

I claim—

40 1. In a figure toy, a support adapted to move bodily over a supporting surface, a body rigidly connected with the support, legs for the body having a pivotal and slideable connection with respect thereto, crank 45 shafts and brackets in which they are

mounted to turn, said crank shafts having cranks, one for each leg set at angles with respect to each other, and means for interconnecting the cranks, whereby when the device is moved over a supporting surface 50 in position for a leg to contact therewith, such contact will cause one leg to give motion to another.

2. In a figure toy, a support adapted to move bodily over a supporting surface, a body rigidly connected with the support, legs pivotally and slidably connected with the body, crank shafts supported from the body and having a plurality of cranks, one connected with each leg and set at an angle 60 to each other, studs projecting from the body, guides on the legs comprising housings having attaching ears, each leg having an aperture therethrough for the passage of one of the ears, a crank for each leg, and means for interconnecting the cranks whereby when the device is moved over a supporting surface in position for a leg to contact therewith, such contact will cause one leg 70 to give motion to another.

3. In a figure toy, a support adapted to move bodily over a supporting surface, a body connected with the support, crank shafts supported from the body, and having a plurality of cranks set at angles with relation to each other, front and rear legs mounted on the cranks, means connecting the body and legs permitting a pivotal and slideable movement with respect thereto, levers connecting the front and rear legs, 80 whereby when the device is moved over a supporting surface in position for a leg to contact therewith, such contact will cause one leg to communicate motion to another.

In testimony whereof, I affix my signature 85 in the presence of two witnesses.

PAUL H. JONES.
